LOOP GUIDE AND METHOD OF APPLYING
LOOPS TO MACHINES

Hugo A. Klahre, Teaneck, N. J., assignor to Consolidated Trimming Corporation, New York, N. Y., a corporation of New York

Application March 16, 1939, Serial No. 262,148

14 Claims. (Cl. 28—2)

This invention relates to improvements in loop guides and to a novel method of applying loops to a machine.

Its object is to provide a simple and inexpensive device for holding the loops of a looped heading and directing them to the path of a movable member of a machine for applying ornamentation to the loops and to the method of using such a device.

Another object is to provide a stationary loop holder with a bifurcated end which straddles a movable die of a fringe machine in such a way that the loops are delivered to a part of such a die one at a time, and are removed from the holder by the movement of the die.

Other objects will appear in the following specification in which I will describe certain structures which embody my invention, the novel features of which I will point out in appended claims.

Referring to the drawings.

Fig. 1 is a plan view of a ball fringe machine with my invention applied to it;

Fig. 2 is a side elevation of the parts shown in Fig. 1;

Fig. 3 is a sectional elevation of a pair of rollers and their adjustable mounting for supporting an end of the guide, the section being taken on line 3—3 of Fig. 1;

Fig. 4 is a plan view on a larger scale of some of the parts of the ball fringe machine and of the bifurcated end of the loop guide, showing the relative positions of the guide and the dies of the machine when the dies are retracted;

Figs. 5 and 6 are views similar to Fig. 4, showing the parts in different relative positions;

Fig. 7 is an end elevation of the parts shown in Fig. 4 and of a roller shown in Figs. 1 and 2.

10 designates the frame of a ball fringe machine. On it are mounted a reciprocatory forming die having two prongs 11 and 12, a cooperating plunger die 13 and a pair of knives 14 and 15. These parts are actuated by cams 16 driven from a shaft 17.

The forming die is moved from its Fig. 4 position to its Fig. 5 position to embrace between its prongs 11 and 12 a tuft 18 which is fed downwardly across its path. The plunger die 13 is moved in the opposite direction to first bend into the form of a staple a piece cut off of a wire 19 and to then force the staple around the tuft and clinch it to bind the strands of the tuft together. If a loop is on one of the prongs of the forming die at the time the wire is applied, the loop is bound to the strands of the tuft.

Knives 14 and 15 are then moved to sever a short section of the tuft which has been bound together and to the loop. These parts and their operation are well known and need no further description.

20 is a tape-like heading having loops 21 projecting from one of its edges at spaced intervals. These loops are loaded onto a guide rod 30, as shown in Fig. 1. The rod is of sufficient length 5 to hold a considerable quantity of the heading. The outer end of the guide rod is secured in a clamp 31 in a standard 32 held at a fixed distance from the frame 10 of the ball fringe machine by a brace rod 33 with sufficient rigidity to prevent its rotation. The other end of the guide rod 30 is supported by a pair of grooved rollers 34, 34 on a bracket on the machine frame 10, which bracket is laterally and vertically adjustable. (See Fig. 3.) These rollers form a loose 15 fit with the guide rod to enable the loops 21 to pass.

The inner end of guide rod 30 is bifurcated and shaped to form two flat spaced fingers 35 which straddle the prongs of the forming die 20 and extend obliquely across them. One side of these fingers is cut back, as at 36, to form a clearance between them and the prongs 11 when the die is retracted, as shown in Fig. 4. Their other side is designated by 37. The longitudinal 25 position of fingers 35, in relation to the forming die, may be adjusted by changing the position of the other end of the guide rod in the clamp 31. The vertical and lateral position of the fingers may be adjusted by some such arrangement as that shown in Fig. 3. The guide rod 30 is sufficiently flexible to provide for these vertical and lateral adjustments.

40 is a roller driven from shaft 17 by suitable means, a belt 41 being shown in Fig. 1 as a diagrammatic representation of a mechanism for this purpose. Roller 40 maintains a tension on the heading 20 in the direction indicated by the arrows.

The operation may be seen by first referring 45 to Figs. 4 and 7. In these figures the dies are in their retracted positions with the fingers 35 overlapping the prong 12. The heading 20 has been advanced by the roller 40 until one of its loops 21A has been pulled off from the fingers 35 onto the prong 12 of the forming die and is held thereon under tension. During this part of the operation there is a slip between the roller 40 and the heading 20. As the forming die advances to the position shown in Fig. 5, the loop 50 21A passes with the die between the fingers 35. At the Fig. 5 position the wire is applied to the tuft 18 and the loop 21A and then the wire encircled part of the tuft is cut off.

Upon the retraction movement of the forming 55 die, the tuft 18 abuts against the surfaces 37 of the fingers which arrests further movement of the loop in that direction, so that as the forming die continues its backward movement its prong 12 slips out of loop 21A. The heading 20 is then advanced to bring the loop shown at 21B

in Fig. 7 to the position of the loop 21A in the same figure and the operation is repeated.

Structural modifications may be made within the spirit and scope of this invention and its use is not confined to the use with the particular mechanism illustrated and described, and I intend no limitations other than those imposed by the appended claims.

What I claim is:

1. The combination of a movable member, stationary spaced fingers for holding the loops of a looped heading, said fingers straddling the movable member, and means for pulling the heading to transfer its loops from the fingers onto the movable member.

2. The combination of a movable member, a stationary guide for the loops of a looped heading, said guide having spaced fingers at one of its ends straddling the movable member, and means for pulling the heading to transfer its loops from the fingers onto the movable member.

3. The combination of a reciprocatory member, stationary spaced fingers for holding the loops of a looped heading, said fingers straddling the member, and means for pulling the heading to transfer its loops from the fingers onto the reciprocatory member.

4. The combination of a reciprocatory member, a stationary guide for the loops of a looped heading, said guide having spaced fingers at one of its ends straddling the member, and means for pulling the heading to transfer its loops from the fingers onto the reciprocatory member.

5. The combination of a reciprocatory member, a stationary guide for the loops of a looped heading, said guide having spaced fingers at one of its ends straddling the member in a position oblique to the path of its movement, and means for pulling the heading to transfer its loops from the fingers onto the reciprocatory member.

6. The combination of a reciprocatory member, stationary spaced fingers for holding the loops of a looped heading, said fingers straddling the member, means for pulling the heading to transfer its loops from the fingers onto the reciprocatory member, said member being arranged to carry the loops through the fingers by its forward movement, and means for arresting the movement of the loops during the backward movement of the member.

7. The combination of a reciprocatory member having a prong, a pair of stationary fingers for holding the loops of a looped heading, said fingers straddling and overlapping said prong, the outer edges of the fingers projecting beyond the end of the prong when said member is in its retracted position to guide the loops over the end of the prong, and means for pulling the heading to transfer its loops from the fingers onto the movable member.

8. The combination of a reciprocatory member having a pair of prongs, a pair of stationary fingers for holding the loops of a looped heading arranged to straddle said prongs, said fingers being so positioned in relation to the prongs that their inner edges clear one of the prongs and overlap the other prong when the member is in its retracted position and their outer edges extend beyond the end of the other prong to guide the loops over the second prong, and means for pulling the heading to transfer its loops from the fingers onto the movable member.

9. A machine for applying tufts to the loops of a looped heading comprising a reciprocatory

two-pronged forming die and means for binding together the strands of a tuft and the loops of the heading, combined with stationary spaced fingers for holding the loops of the heading, said fingers straddling the forming die and means for pulling the heading to transfer its loops from the fingers onto one of the prongs of the forming die.

10. A machine for applying tufts to the loops of a looped heading comprising a reciprocatory two-pronged forming die and means for binding together the strands of a tuft and the loops of the heading, combined with a stationary guide for the loops of the heading, said guide having spaced fingers at one of its ends straddling the forming die in a position oblique to the path of its movement, and means for pulling the heading to move its loops past one of the prongs of the forming die and to transfer said loops onto the other prong of the die.

11. A machine for applying tufts to the loops of a looped heading comprising a reciprocatory two-pronged forming die and means for binding together the strands of a tuft and the loops of the heading, combined with stationary spaced fingers for holding the loops of the heading, said fingers straddling the forming die, and means for pulling the heading to transfer its loops from the fingers onto the movable member, said die being arranged to carry the loops through the fingers by its forward movement to be bound to the tuft and said fingers being positioned to engage the tuft to arrest the movement of the loops during the return movement of the die.

12. A machine for applying tufts to the loops of a looped heading comprising a reciprocatory two-pronged forming die and means for binding together the strands of a tuft and the loops of the heading, a stationary guide for the loops of the heading, said guide having spaced fingers at one of its ends straddling the forming die in a position oblique to the path of its movement, and means for pulling the heading to move its loops past one of the prongs of the forming die and to transfer said loops onto the other prong of the die, said die being arranged to carry the loops through the fingers by its forward movement to be bound to the tuft and said fingers being positioned to engage the tuft to arrest the movement of the loops during the return movement of the die.

13. The herein disclosed method of applying the loops of a looped heading to a longitudinally movable part of a machine for affixing material to said loops, which consists of applying a continuous tension to the heading to pull the heading transversely across said longitudinally movable part of the machine, and guiding the loops in open condition into the path of said longitudinally movable part of the machine.

14. The herein disclosed method of affixing material to the loops of a looped heading, which consists of applying a continuous tension to the heading to pull the heading transversely across a longitudinally movable part of a machine for affixing material to the loops, holding a loop in open condition in the path of said longitudinally movable part of the machine, utilizing the movement of such part of the machine to move the open loop to a material receiving position, affixing material to the loop and utilizing the affixed material to arrest movement of the loop away from the material applying position.

HUGO A. KLAHRE.
